(57) **CLAIM**

The ornamental design for a video processing apparatus, as shown and described.

DESCRIPTION

FIG. 1 is a top, front perspective view of a video processing apparatus showing our new design in a first embodiment; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; and FIG. 8 is a detail view thereof within line 8 of FIG. 1. FIG. 9 is a top, front perspective view of a video processing apparatus showing our new design in a second embodiment; FIG. 10 is a front view thereof; FIG. 11 is a rear view thereof; FIG. 12 is a left side view thereof; FIG. 13 is a right side view thereof; FIG. 14 is a top view thereof; FIG. 15 is a bottom view thereof; and FIG. 16 is a detail view thereof within line 16 of FIG. 9. Uniformly-sized broken lines illustrate portions of the video processing apparatus that form no part of the claimed design. Long-short broken lines illustrate boundaries of the claim and form no part of the claimed design. Long-short-short broken lines indicate portions of the claimed design that are illustrated in enlargements, and the long-short-short broken lines form no part of the claimed design.

1 Claim, 16 Drawing Sheets

Related U.S. Application Data

division of application No. 29/782,239, filed on May 5, 2021, now Pat. No. Des. 989,306.
